OIL BURNER AND MOTOR UNIT

Edward L. Wood, Detroit, Mich., assignor to Gar
Wood Industries, Inc., Detroit, Mich., a corpora-
tion of Michigan

Application August 11, 1937, Serial No. 158,560

2 Claims. (Cl. 158—77)

My invention relates to oil burners, and particularly to a unit burner having a motor upon which the burner elements are retained in axial alignment with the motor shaft.

The main objects of my invention are to provide a burner unit with resilient mounting means which frictionally supports the unit on an air conditioning device; to provide a unit embodying a motor having a pump, air propelling means, and nozzle forming a unit which is resiliently and releasably mounted by the supporting means of the motor; to provide a motor with a pump, both of which have co-axial hollow shafts which terminate in a low pressure side of the pump; to join the terminal ends of a pump and motor which are disposed in the low pressure side of the pump with a connector which forms a conductor and a driving means between the shafts; to provide a nozzle having a hollow shaft with radially disposed passageways for the liquid which is delivered to a chamber in the end of the nozzle to rotate in the direction of the rotation of the shaft; to provide a heating device with a cylindrical element for frictionally receiving the burner unit which forms a seal therewith; and in general, to provide a unit burner which is rugged in construction, positive in operation, and economical of manufacture.

Other objects and features of novelty of my invention will be either specifically pointed out or will become apparent when referring, for a better understanding of my invention to the following description taken in conjunction with the accompanying drawings, wherein:

Figure 1 is a sectional view of an oil burner unit embodying features of my invention;

Fig. 2 is a reduced sectional view of the structure illustrated in Fig. 1, taken on the line 2—2 thereof;

Fig. 3 is a sectional view of the structure illustrated in Fig. 1, taken on the line 3—3 thereof;

Fig. 4 is an enlarged sectional view of the nozzle illustrated in Fig. 1;

Fig. 5 is an enlarged sectional view of the structure illustrated in Fig. 4, taken on the line 5—5 thereof;

Fig. 6 is a broken view of a pump unit similar to that illustrated in Fig. 1, showing a modified form thereof; and,

Fig. 7 is an enlarged broken view of the centrifugal switch illustrated in Fig. 1.

Referring more particularly to Fig. 1, I have illustrated the unit oil burner as being mounted in a tubular element 10 which projects through

the casing 11 of the conditioning unit and wall 12 of a heating chamber. The cylindrical element is preferably welded to the furnace or conditioning unit, and it is to be understood that the element is a necessary part of the burner unit and can be employed separately therewith. A collar 14 is welded or otherwise secured on the inner surface of the element 10 near the inner end thereof and forms an abutment for an air deflecting element 15 which is retained in fixed abutted position by a plurality of bolts 16. The air deflecting element has a tapered wall terminating in a cylindrical neck 17 which receives an annular ring 18 of a triangular section to further control the flow of air across the nozzle of the burner. The ring 18 is slotted at 20 at the bottom as illustrated in Fig. 1, and is provided with a sloping entrance surface 19 by which it may be readily forced into the neck 17 of the air deflector element. A sector 21 is welded or otherwise secured at the rear lower end of the neck 17 to form a wall for trapping any oil which may drip from the nozzle of the burner and which may pass from the slot 22 in the ring 18.

The burner unit is completely demountable and slides within the cylindrical element 10 to frictionally engage the wall thereof at spaced points to provide a support for the unit. In this construction the unit 23 may be bodily removed from the element 10 by removing a cap 24 and disconnecting the supply and return conduits 25 and 26. The unit is retained in position by the frictional engagement of the supporting elements with the wall, which elements are resilient and sound insulating.

The unit comprises a motor 27, a liquid pump 28, a fan 29, and a nozzle 31. On the rear bracket of the motor a plurality of rubber supporting fingers 32 are provided of such length as to engage the element 10 under compression to thereby resiliently support the rear end of the unit. A guard or auxiliary support 33 may be provided adjacent to the lower or all of the fingers 32 as a safety element to prevent the unit from sagging in case the rubber in the fingers 32 should deteriorate to such an extent as to fail to support the unit. The guard will form the support for the unit to retain the unit in operation until new fingers 32 can be provided.

On the front bracket of the motor, supporting elements 34 are provided to which a ring 35 is secured having a channel 36 formed on its periphery for retaining a resilient ring 37 which may be made of asbestos or other similar material

to form a seal with the element 10 and a further support for the unit. It will thus be seen that the unit is floated upon the ring 37 and the fingers 32 and retained in position by the frictional engagement thereof with the wall of the element 10.

On the rear bracket of the motor 27, the pump 28 is secured to form a unit therewith. Any suitable pump 28 may be employed, the one herein illustrated being provided with the usual gears 38 having the driving shaft 39 thereof disposed in extension of the hollow shaft 41 of the motor 23. The ends of the shafts abut within the low pressure chamber 46 of the pump and thereby eliminates the hazard of leaks between the shafts. A sealed drive connection is provided between the shafts by a tube 42 having caps 43 threaded on each of its ends for drawing resilient washers 44 against the shafts when the caps are tightened upon the tube. A seal 45 within the low pressure chamber 46 seals the motor shaft within the low pressure chamber 46 of the pump. Fluid is drawn through the conduit 25 when the gears 38 are operated and is forced through the regulating valve 30, the hollow shaft 20 into the opening 47 and the end of the shaft 39. Any fluid which may leak past the valve or be by-passed thereabout, will return to the supply source through the conduit 26.

Referring to Fig. 6, I have illustrated a modified form of pump wherein the pressure on the shaft is balanced. In the structure of Fig. 1, the fluid was conducted from the regulating valve 30 through the idler gear shaft to a slot which communicated with the end of the driven gear shaft. In the present arrangement the fluid from the regulating valve passes through the aperture 40 to an annular groove 50 in the shaft which communicates with the opening in the shaft. The rear end of the shaft is closed and the pressure therewithin is balanced, eliminating the necessity of employing thrust washers which are subjected to extreme wear.

On the opposite end of the shaft 41 a hollow hub 51 of the air propelling element 29 is threaded or otherwise secured. The element 29 is provided with a plurality of blades 52 supported by a plate 55, the end portions 53 of the blades being disposed at an angle, as illustrated more clearly in Fig. 3. Air is drawn through an opening 54 in the ring 35, moved along the blades 52 and plate 55, propelled along the wall of the air deflector element 15 and ejected from the end of the neck 17.

Referring more particularly to Figs. 1 and 7, I have illustrated the centrifugally actuated valve as being mounted in the nozzle 31 and hub 51 of the air propelling means 29. The valve embodies a movable valve element 58 pivoted to a pivotally mounted arm 59 having a weight 61 on its opposite end. A hairpin type of spring 62 has a U-shaped end disposed about the arm 59 for urging the arm counter-clockwise and moving the element 58. The element 58 comprises a small rod 65 having a semi-spherical valve portion 63 secured thereto inwardly of the end thereof. A spherical seat 64 is formed in the valve housing upon which the valve portion 63 seats and through which the end of the rod 65 projects. A pivot 60 supports the arm 59 adjacent to the pivotal connection of the rod 65 therewith. The distance of the spring 62 from the pivot 60 is greater than the distance of the rod 65 therefrom so that the moment of the spring is sufficient to produce a snap action to the valve to provide instantaneous closing as soon as the speed of the motor is re-

duced. The valve is loosely guided by the free end of the rod and the valve portion 63 is self-centering on the seat 64 irrespective of the degree of tilt of the rod 65.

At the base of the hub 51 a shouldered washer 66 is secured. The washer has a central opening covered by a screen 67 disposed in the path of the fuel from the pump 28. Any particles caught by the screen will be moved by centrifugal action toward the outer periphery of the washer which forms a catch basin therefor.

The arm 59 may be provided with a threaded aperture 57 and the weight 61 is preferably of lead or similar soft material which is bent in U-shape and pressed onto the arm with sufficient force to have the material flow into the threaded aperture to thereby retain the weight in firm fixed relation to the arm.

Over the outer end of the cylindrical element 10 a casing 24 is secured having a slotted end 68 with brackets 69 disposed at each side through which clamping bolts 73 extend to draw the brackets together and retain the cap in position. The conductors 25 and 26 extend through the opening 14 formed by the slot in the cap through which the air required for combustion is drawn by the air propelling element 29. A shutter 75 is secured adjacent the opening by a bolt 76 adjustable in a slot 77 in the cap 24. By shifting the shutter 75 a proper regulation may be had for the air to be delivered through the neck 17 of the air deflector 15. Suitable electrodes 78 are provided adjacent to the nozzle within the neck 17. The transformer 79 for energizing said electrodes is herein illustrated as being supported within the casing 11 on the outer surface of the cylindrical element 10 by suitable screws 81.

Referring more particularly to Figs. 4 and 5, I have illustrated the nozzle 31 as embodying a conductor 91, having a cap 92 threaded in its outer end. The cap supports a sealing element 93, having a frusto-conical head 94 and a recessed portion forming a chamber 95. The head 94 forms a seal with the wall of a similarly shaped recess within the cap 92. Slots 96 are formed in the head 94 disposed tangentially of the head as illustrated in Fig. 5. The ends of the slots communicate with a chamber 97 in the end of the cap which is extended to form an arcuate delivery passage 98, the curvature of which controls the included angle of the conical shaped spray of fluid delivered from the nozzle end. A passage 99 extends through the element 93 communicating with the chamber 95 within the cap.

A thimble 101 is screwed within the end of the cap 92 having openings 102 in its wall and provided with a shoulder 103 on its lower end. An annular screen 104 is mounted on the thimble 101 in a position to be engaged by the cap 92 and the shoulder 103 when the thimble 101 is threaded into the cap. A further seal for the fluid is thereby provided in the nozzle to thereby eliminate any possibility of stoppage in the fluid passages. The slots 96 control the flow of fluid under pressure from the nozzle and when disposed in the manner illustrated can be made larger than when forming a direct passage. The fluid is introduced under pressure, which may be as high as 100 pounds per square inch, and is swirled within the chamber 97 as it is propelled from the end of the passage 98. The frictional resistance which is set up by the wall of the opening is reduced materially through the rotation of the shaft in the direction of the flow of fluid and it was found that a more turbulent mixture was ob-

tained which broke down the fluid into smaller globules. These are ejected from the passage 98 in a very fine spray in the shape of a cone, the included angle of which is regulated by the degree of arc provided at the mouth of the passage. The terminal ends of the electrodes are disposed within the cone of spray and assurance is always had that ignition will occur when the burner is operated. The ring 18 provided in the neck 17, directs the propelled air across the conical spray to uniformly mingle with the small fluid globules and provide a mixture which is readily combustible.

The unit thus formed is self-contained and is releasably and resiliently mounted and sealed within the cylinder element 10 which forms a part of the device. Connections are made through conductors 25 and 26 which project through the opening 74 in the end cap 24. It is only necessary to remove the cap and disconnect the conductors to have the unit free to be removed by withdrawing it from the cylindrical element. The unit thus removed may be repaired, or a repair unit may be immediately installed in place of the defective unit. It is to be understood that the motor and pump forms a unit which may be employed for other purposes where a hollow rotating shaft for delivering fluid can be utilized.

While I have described and illustrated but a single embodiment of my invention, it will be apparent to those skilled in the art that various changes, omissions, additions, and substitutions may be made therein without departing from the spirit and scope of my invention, as set forth in the accompanying claims.

I claim as my invention:

1. A liquid fuel burning unit of the horizontal type having a resilient annular element at one end for sealing the unit to a cylindrical wall, spaced rubber blocks at the opposite end of the unit also engaging the cylinder wall for frictionally and removably mounting the unit therein while providing a passage for air between said blocks.

2. A liquid fuel burning unit of the horizontal type, including in combination, a motor, a hollow shaft for said motor, a fuel delivering nozzle on said shaft, a pump driven thereby, a hollow shaft in said pump, a regulating valve, means for introducing liquid from said pump to said valve and from said valve through said hollow pump shaft and from said pump shaft to said hollow motor shaft from which it is sprayed by said nozzle.

EDWARD L. WOOD.
